ANIMATED SIGN AND METHOD OF OPERATING IT

John Gordon Best, Toronto, Ontario, Canada, assignor to General Animated Signs, Limited, Toronto, Ontario, Canada, a company of Ontario, Canada

Application December 10, 1937, Serial No. 179,196
In Canada February 12, 1937

9 Claims. (Cl. 40—130)

The present invention relates to animated signs and is more particularly concerned with illuminated animated signs of the character in which an illusion of animation is brought about by varying the color of the sign illumination. The invention is further concerned with methods of animating such signs to produce special effects.

The illusion of animation produced according to my invention is due wholly to the physiological and psychological effects caused by my special lighting, color and background arrangements.

The basic or primary animation is physiological and is based upon well known optical color laws such as color reflection and absorption, etc.; frequency of cyclic color changes; color and background combination in the sign and color combination in the illuminating means for the sign; and physiological effects and phenomena such as chromatic aberration, irradiation, etc.

20 The basic animation is presented when the cyclic color change of the sign illuminating means is between certain limits of frequency. With proper conditions the illusion of animation is produced in the range between one and twenty cyclic color changes per second. However, in certain cases, as where an illusion of natural directional motion is desired to accompany the basic animation, the range is preferably between one and one-half and four cyclic color changes per second.

It is a major object of my invention to provide novel animated signs and methods of operating the same wherein the illusion of animation is obtained by illuminating the sign with lights of different colors.

A further object of my invention is to provide a novel animated sign in which the illusion of animation is physiologically produced.

40 A further object of my invention is to provide a novel animated sign in which an illusion of natural movement is psychologically produced.

Another object of my invention is to provide a sign which will have normal advertising value in the daytime when not being illuminated.

45 A further object of my invention is to provide a sign having distinctively colored indicia markings upon a neutral background and which is illuminated alternately by light which has the same predominant hue as part of the colored indicia and by light of a different color whereby an illusion of animation is produced.

Another object of my invention is to provide an animated sign having certain portions of the indicia animating and certain portions non-55 animating and having suitable illuminating

means for creating an illusion of animation at the animating portions of the indicia. In one embodiment of my invention the non-animating portions appear stationary and serve as message bearing indicia only. In another embodiment of my invention the non-animating indicia are of such form or of such a nature as to produce a psychological effect of natural motion in the indicia which supplements and amplifies the basic animation produced by color changes in the illuminating means.

Further objects of my invention will become apparent as the specification proceeds in connection with the annexed drawings, and from the appended claims.

In the drawings:

Figure 1 is a perspective view illustrating an arrangement by which my indicia bearing sign may be illuminated to produce animation effects according to the invention.

Figure 2 is a modified form of the sign surface and indicia of Figure 1.

Figure 3 is a still further modified form of the sign surface and indicia of Figure 1.

Figure 4 is a front view of a sign forming part of my invention and illustrates a manner of creating an illusion of natural movement of an object. Here, specifically, a circle may be made to appear to rotate in a specific direction.

Figure 5 illustrates another sign embodying my invention and illustrates a manner of creating an illusion of natural movement of a bird. Here the animated parts are integral with the object which appears to move.

Figure 6 shows another sign according to my invention illustrating how an illusion of natural movement of flames from a fire may be produced.

Figure 7 shows a further sign embodying my invention in which an illusion of motion of a vehicle is produced. Here the animating parts are separate from the object which appears to move.

Figure 8 is a partially diagrammatic view of a suitable form of illuminating means for giving alternate flashes of different colored light and which may be used with any of the signs of the invention.

Before proceeding with a detailed description of the invention it will be helpful to define the various terms used in the specification and claims.

By "indicia" I mean markings at the surface of the sign. The indicia may be animating or non-animating and may be pictorial or non-pictorial. The indicia may combine to define an

object, or may be entirely separate from each other, or may be superposed at least in part.

By "background" I mean the portions of the sign contacting the whole or a major portion of the periphery of the indicia and extending outwardly therefrom an indeterminate distance. Thus the background may be merely an outline or border around the indicia, or may be the whole or a large portion of the field upon which the indicia are displayed. For instance, the indicia may assume the form of figures or letters and may have a contrastingly colored border of neutral or non-neutral color and in such case the borders can be regarded as the background.

15 By "illumination" I mean the casting of colored lights upon the sign in accordance with this invention.

By "neutral color" I mean a color that has no distinguishing or dominant hue. Examples of such are white, black, grey or brown.

By "dominant hue" or "distinguishing hue" I mean a color which has a predominant wave band which makes the light appear to an observer to be of particular color. For example, a light 25 which an observer might call "red" may contain some yellow or blue light which is not apparent due to the overwhelming preponderancy of wave bands in the red portion of the visible spectrum. Thus, whenever I state that a light has a "dominant hue" or is of a certain "color" I means to include not only substantially monochromatic light but also impure colors which generally have the same appearance as the monochromatic light. A specific example of this is that when I say "red" 35 I mean to include among others, impure colors generally known as magenta and scarlet but which have predominant red wave bands.

By "cyclic color change" I mean the exposure of the sign to light of one color for its full time 40 interval and to the other color through its full time interval and until the beginning of the next exposure of the sign to light of the first color.

By "non-animating" I mean that the part or parts referred to are colored in colors, including 45 neutral colors, which are not animated when subjected to light which animates other portions of the sign.

In amplification of the nature of non-animating colors, the properties of a color which render it non-animating are:

50 (a) Its ability to reflect back both of the colors alternately cast upon the sign. Such colors may be white, grey, brown, yellow, etc.

(b) Its ability to absorb both colors cast upon 55 the sign. Such colors may be black, dark blue, etc.

By "basic or primary animation" I mean the illusion of animation produced physiologically by the alternate lighting arrangement of my invention. This is to be distinguished from the 60 illusion of natural movement or directional motion which is psychologically produced. This psychological illusion amplifies and gives direction to the physiologically created basic animation.

65 By "discrete" I mean separate and individual images are observed as distinguished from images which, due to the persistency of vision, optically blend and appear continuously visible.

70 With reference to Figure 1 a sign 11 having a background 12 is illuminated by light from a suitable source 10. The indicia upon background 12 consists of a primary or animating part 13 and a secondary or non-animating part 14.

75 Background 12 may be of any suitable color such

as a non-neutral color, or a color complementary to that of part 13.

Animating part 13 which may be composed of one or several different co-operating or non-co-operating representations, is colored in a color which 5 has a distinguishing or dominant hue. Since colors having high energy value are preferred in signs, the animating color is preferably red although any color may be selected as desired.

Non-animating part 14, which may or may not 10 be composed of one or several different co-operating or non-co-operating representations, is colored in a color which may have a dominant hue or may be neutral, but which is selected to be constantly visible no matter what color is being 15 projected on the sign.

The sign is preferably illuminated by a projector which casts differently colored lights alternately upon the same.

Such a projector may comprise a pair of lamps 20 before each of which is disposed a light filter of suitable color with the lamp circuits controlled by suitable flasher switches, or may comprise the rotatable color filter assembly of Figure 8, later to be described.

One of these color screens or filters is designed to pass light which has the same dominant hue as the animating color on the sign. The other color screen or filter is designed to pass light which is deficient in the dominant hue of the animating 30 indicia. In practice it has been found very satisfactory to project complementary colored lights upon the sign. For example, where red primary indicia markings are used, red and green lights are projected on the sign. The secondary or non-animating indicia markings are of course of such color as to reflect or absorb both red and green.

Suitable and preferable animating indicia colors are red, green and blue. Suitable and preferable non-animating colors are yellow, orange, green, 35 blue or violet or even a neutral color.

The non-animating indicia may be located upon the same colored background as the animating indicia or may have provided for it a background of a different color.

45 In operation the flasher in the circuit of the lamps in projector 10 is operated to alternately and successively light these lamps thereby casting alternate flashes of differently colored light upon the sign 11. When light of the animating 50 color falls on the sign the primary animating portion 13 and the non-animating portion 14 are both visible to an observer but, when the non-animating light is being projected, portion 13 is not visible in its own color because the non-animating light is deficient in the dominant hue of portion 13 and will therefore not be reflected or transmitted thereby.

Hence the observer views a sign background upon which the primary indicia are alternately 60 visible and the secondary indicia are constantly visible. When the cyclic color frequency has been regulated properly the primary part 13 will be seen alternately as discrete images and will present an appearance of animation comprising a 65 pulsating movement due mostly to the effect of chromatic aberration in the eye and a bodily movement in space relative to the background. In some cases there is a stereoscopic effect so that the indicia appears to stand out from the 70 background.

The frequency at which the cyclic color change takes place must be high enough to allow the observer to gain a sense of animation, but must not be so high as to optically merge the images 75

of the primary part because of persistence of vision and therefore make them constantly visible. Preferably the range of cyclic color change should be in the neighborhood of from one and one-half to four cyclic changes per second for best practical results.

This illusion of animation is the primary or basic animation which the present invention produces. A few examples of specific lighting arrangements are given to show the flexibility of this principle. Some equivalent light methods for animating a sign having red primary indicia are listed below.

(a) Red and green lights may be alternately cast on the sign.

(b) A green light may be kept on continuously and a red light alternated on and off at suitable frequencies.

(c) A red or green light may be kept on continuously and a polychromatic or orthochromatic light alternated on or off at suitable frequencies.

(d) Red light and poly- or orthochromatic light may be alternated on or off at suitable frequencies.

(e) Green light and polychromatic or orthochromatic light may be alternated on or off at suitable frequencies.

The particular method of lighting will depend on the nature of the sign and the kind of animation desired.

In the sign of Figure 1 the animated primary indicia serves to catch and hold the attention of an observer. The secondary non-animating indicia conveys the advertising message to the observer.

In Figure 2 is illustrated an embodiment of the invention comprising a sign 21 having a background 24 upon which are disposed animating indicia 22, which are colored in a color having a distinguishing hue corresponding with one of the colors of the lighting device. Indicia markings 23 on that background are neutral in color. The background may be of any non-animating color except the color used for indicia 23.

When illuminated by the light arrangement described above in Figure 1 indicia 22 will appear to animate while indicia 23 will be constantly visible at all times. Of course, the relative colors of indicia 23 and the background may be selected so that either may be substantially non-reflective, as would be the case if colored black, while the other is highly reflective if colored white, grey, yellow, etc.

Another embodiment of the invention is illustrated in Figure 3 where a sign 29 comprises a background 31 on which is disposed animating indicia 30 and 32 colored in a suitable animating color. A portion 33 of the background is colored differently from the remainder of the background and has disposed thereon non-animating indicia 34 colored in suitable non-animating colors. Background 33 is preferably neutral in color.

For practical purposes the non-animating colors here may be yellow, orange, pale blue, pale green, pale violet or even neutral. It may be here pointed out that any color heavily shaded with black such as dark blue, dark violet, dark green, etc. may be considered the full equivalent of black for purposes of the invention.

The embodiments of the invention illustrated in Figures 4-7 are mainly concerned with creating illusions of natural directional motion or movement and involve the addition of motion indicating indicia to supplement the animation producing effects above described.

In Figure 4 a sign 35 is provided preferably with a neutral background 36 upon which is disposed an annular ring or circle 37 colored in a suitable animating color such as red. A plurality of arrows 38 are associated with circle 31 and all point in the same direction of motion. Arrows 38 are colored in a non-animating color so as to be continuously visible. Here the non-animating indicia is separate from the pictorial representation.

When such a sign is alternately lighted as described above and at a rate of from one and one-half to four cyclic changes per second, an illusion of animation is created in the animating indicia or circle 37. This illusion is supplemented and amplified and given directional characteristics by the presence of arrows 38 so that circle 37 appears to rotate in the direction of the arrows or clockwise as shown in Figure 4. This illusion of directional movement is produced psychologically and is suggested by the non-animating indicia and if the arrows pointed in the opposite direction the circle would appear to so rotate.

In Figure 5 a sign 39 has a neutral background 40 upon which a bird is pictorially disposed. Wing portions 41 are colored in an animating color while the body 42 is colored in a non-animating color. When this sign is subjected to the lighting arrangements described above wings 41 appear to pulsate or flap while, since body 42 is pointed in a particular direction, the whole bird appears to move to the right in Figure 5. This illusion of motion is produced by the association in the observer's mind of flapping wings with a moving bird. Here both sets of indicia combine to form the pictorial representation of the object.

In Figure 6 is illustrated a sign 49 having a neutral background 50 upon which are disposed pictorially fuel 51 in non-animating color, yellow 40 flames 52 and red flames 53. When this sign is cyclically illuminated as above described the red flames appear to move upward in a natural and flamelike manner while the fuel and the yellow flames appear relatively stationary.

The embodiment of the invention shown in Figure 7 involves an arrangement opposite to that of Figure 4 in that the indicia which appears to move is here colored in non-animating colors. Figure 7 shows a sign 54 having a neutral background 55 upon which an automobile 56 is portrayed in non-animating color. A series of lines 57 in animating color such as red are disposed behind the automobile. When this sign is cyclically illuminated the red lines appear to animate and impart to the automobile an illusion of natural and directional movement. Here the animating indicia are separate markings which impart an illusion of natural motion to a separate non-animating indicia.

A further form of color changing mechanism which may be used is shown at Figure 8 in which substantially white light from a suitable source 58 passes through a condenser 59 and then through a rotating color wheel or shutter 60 65 driven by a suitable constant or variable speed motor (not shown) and which has two different color segments or filters 61 and 62. Beam 63 is projected upon any of the color signs above described. It will be obvious that beam 63 is alternately of different colors in practicing the invention.

Although the above disclosed embodiments of my invention specifically illustrate signs in which the color effects are attained through reflected 75

light from suitably colored portions of the sign, it will be apparent that the invention is equally well applicable to signs having translucent or transparent color portions for producing the same effects. Where such light permeable signs are used, the source of light such as the projector of Figure 8 is located behind the sign and the modified light is transmitted to the eye of the observer. Furthermore translucent signs may 10 be used to produce the same lighting effects.

For carrying out my invention where an illusion of natural or directional movement is desired, the object to be given the appearance of motion should be studied and analyzed. The 15 best arrangement of animating and non-animating lines should be selected for the sign. For example, it may be best to locate the animation producing lines entirely separate from the object to be animated and which appears to move 20 as in Figure 7.

Selection of the frequency of cyclic color change depends upon the character of the object portrayed. For example, the frequency when showing a gull in flight would be lower than that 25 employed to show liquid flow from a bottle or a speeding automobile. In most cases, while the primary or basic animation may be small the secondary or psychological effect is usually amplified and quite natural.

The invention may be embodied in other specific forms without departing from the spirit or essential characteristics thereof. The present embodiment is therefore to be considered in all respects as illustrative and not restrictive, the 35 scope of the invention being indicated by the appended claims rather than by the foregoing description, and all changes which come within the meaning and range of equivalency of the claims are therefore intended to be embraced 40 therein.

What is claimed and desired to be secured by United States Letters Patent is:

1. In an animated sign, a background of neutral color, indicia upon said background, said indicia comprising a primary part which is colored in a single animating color having a dominant hue and a secondary part which is colored in a non-animating color and means for illuminating said sign in such a manner as to produce and convey to the eyes of an observer the illusion of animation in said sign, and to render said primary part intermittently distinctly visible in contrasting relationship to said secondary part, said illuminating means effecting periodic exposures 50 of said sign to light of substantially the same dominant hue as the animating color and said said periodic exposures being spaced by exposures of said sign to light whose dominant hue is different from that of the animating color.

60 2. In the animated sign defined in claim 1, said illuminating means being operable to project said light upon said sign with a cyclic color frequency of from one and one half to four cycles per second, said frequency being sufficient 65 to effect smooth animation of said indicia but yet sufficiently low to avoid fatigue of the human eye due to rapid color change.

70 3. In an animated sign, a neutral color background, indicia on said background, said indicia having a primary part of comparatively small area with respect to the area of the background and being colored in a single animating color having a distinguishing hue and a secondary part colored in a non-animating color, and means for 75 illuminating said sign alternately with lights of

different colors, one of said lights being of substantially the same color as said primary part and the other of said lights being deficient in the distinguishing hue of said primary color, whereby an illusion of animation is conveyed to the 5 eyes of an observer, said primary part of said indicia smoothly animating in sharp contrast to said background, the absence of animating color in the latter avoiding fatigue of the human eye and causing the single colored primary part of 10 said indicia to stand out in predominating relationship on said background.

4. In an animated sign having a two part background, indicia upon said background, said indicia comprising a primary part colored in an 15 animating color and located on one part of the background and a secondary part of non-animating color located on the other part of said background and means for illuminating said sign alternately with lights of different color, said 20 background parts being differently colored with one of said background parts being neutral in color and the other of said background parts being non-neutral in color.

5. In an animated sign of the type described 25 in claim 4, said primary part being predominantly red and located upon a background of substantially complementary color.

6. The method of making animating signs which comprises analyzing the subject to be animated, providing a background of neutral color, pictorially representing upon that background an inherently animate part of the subject colored in an inanimate color, pictorially representing upon the same background another part colored 35 in a single animate color and being of comparatively small area with respect to the area of the background and alternately illuminating said sign with light rays of animate and inanimate color whereby the combined physiological and 40 psychological influences of said lighting create an illusion of animated natural movement of said subject, said single animate colored part smoothly animating in sharp contrast against said background, the absence of animating colors 45 in the latter avoiding fatigue of the human eye and subordinating said background to said animate colored part of said sign.

7. Apparatus for producing a psychologically induced optical illusion of animation in a sign 50 having indicia of suitable animating color upon a background of neutral color comprising means for alternately illuminating the sign with lights of different colors, one of which has the same predominant hue as the color of the animating 55 indicia and the other of which has a different predominant hue, said alternations having a frequency of greater than one and one-half and less than four cyclic color changes per second, said frequency being sufficient to effect smooth 60 animation of said indicia but yet sufficiently low to avoid fatigue of the human eye due to rapid color change.

8. The method of producing an optical illusion of animation in a sign having indicia of suitable animating color upon a background of neutral color which comprises alternately illuminating the sign with lights of different colors, one of which has the same predominant hue as the color of the animating indicia and the other of which has a different predominant hue, said alternations having a frequency of greater than one and one-half and less than four cyclic color changes per second, said frequency being sufficient to effect smooth animation of said indicia 75

but yet sufficiently low to avoid fatigue of the human eye due to rapid color change.

9. In an animated sign, a background of neutral color, indicia upon said background, said indicia comprising a pictorial primary part which is colored in a single animating color and a secondary part which is colored in a non-animating color, said primary pictorial part being of comparatively small area with respect to the area 5 of said background and means for successively illuminating said sign with lights of different dominant hues, one of said lights having its dominant hue substantially the same as that of the animating color whereby said primary part is alternately visible and said secondary part is continuously visible and an illusion of animation of said primary part is conveyed to the observer, said non-animating secondary part comprising lettering pictorially distinct from said primary part but being a component part of the sign, said pictorial primary part of said indicia smoothly animating in sharp contrast against said background, the absence of animating color in the latter avoiding fatigue of the human eye 10 and causing said primary part to vividly stand out from said background and predominate thereover.

JOHN GORDON BEST.
